CLAIM

The ornamental design for a cryogenic device, as shown and described.

DESCRIPTION

FIG. 1 is a front isometric view of a cryogenic device.

FIG. 2 is a back isometric view of the device of FIG. 1.

FIG. 3 is a front view of the device of FIG. 1.

FIG. 4 is a back view of the device of FIG. 1.

FIG. 5 is a left side view of the device of FIG. 1.

FIG. 6 is a right side view of the device of FIG. 1.

FIG. 7 is a top view of the device of FIG. 1; and,

FIG. 8 is a bottom view of the device of FIG. 1.

The broken lines indicate unclaimed portions of the cryogenic device that form no part of the claimed design.
